Des. 237,484
Patented Nov. 4, 1975

237,484

MOTORCYCLE SADDLE BAG

Harold H. Larsen, Long Beach, and Robert E. Oehring,
Norwalk, Calif., assignors to Bates Industries, Inc.,
Long Beach, Calif.

Filed Mar. 14, 1974, Ser. No. 451,043

Term of patent 14 years

Int. Cl. D12—11

U.S. Cl. D12—158

FIG. 1

FIG. 2

FIG. 3

FIG. 4

FIG. 5

FIG. 6

FIG. 1 is a perspective view of a motorcycle saddle bag showing our new design;

FIG. 2 is a rear elevational view thereof;

FIG. 3 is a right side elevational view thereof;

FIG. 4 is a front elevational view thereof;

FIG. 5 is a top plan view thereof; and

FIG. 6 is a bottom plan view thereof.

We claim:

The ornamental design for a motorcycle saddle bag, substantially as shown.
